CIRCULAR KNIT TUBING CUTTER ATTACHMENT FOR SEWING MACHINES

Charles A. Schaeffer and Clifton C. Foil,
Port Carbon, Pa.

Application February 13, 1937, Serial No. 125,663

2 Claims. (Cl. 112—122)

This invention relates to new and useful improvements in sewing machines and more particularly to an attachment whereby knit tubing can be longitudinally slit as it is advanced toward the needles of the machine.

Heretofore circular knit tubing was sewed to the edge portion of the garment which made a wrong side and a right side thereof. However, the principal object of the present invention is to provide a cutting attachment for sewing machines of this character whereby the knit tubing is cut longitudinally and then brought with its edge portions to a position against opposite sides of the edge portions of a garment, so that by sewing the tubing to the garment in this position both the outside and the inside of the edge portion of the garment are alike.

Other important objects and advantages of the invention will become apparent to the reader of the following specification.

In the drawings:—

Figure 1 represents a fragmentary side elevational view of the sewing machine showing the attachment in place.

Figure 2 is a fragmentary top plan view of the cutting assembly.

Figure 3 is an end elevational view of the cutting assembly.

Figure 4 is a perspective view of one blade of the scissors.

Figure 5 is the movable blade of the scissors.

Figure 6 is a longitudinal sectional view through the movable scissors blade and showing how it is connected to its corresponding shaft.

Figure 7 is a perspective view of the bracket.

Figure 8 is a fragmentary side elevational view of the eccentric arm connected with the scissors.

Figure 9 is a sectional view taken substantially on the line 9—9 of Figure 8.

Figure 10 is a perspective view of the bracket shown in Figure 8.

Figure 11 is a fragmentary side elevational view of the primary guide for the tubing.

Figure 12 is a top plan view of the guide shown in Figure 11.

Figure 13 is a fragmentary front elevational view of a garment after the tubing has been applied in accordance with the execution of the present invention.

Figure 14 is a sectional view of the garment taken substantially on the line 14—14 of Figure 13.

Referring to the drawings wherein like numerals designate like parts, it can be seen that the numeral 5 generally refers to a conventional sew-

ing machine of the type employed for sewing said tubing to the edge portions of garments and this briefly consists of the case 6 on which the usual rocking arm 7 is located as well as the eccentric arm 8.

As is shown in Figure 8, the rocking arm 7 is provided with a laterally disposed trunnion 9 which is disposed through the sectional bearing 10 which is adjustably secured as at 11 to one end of the eccentric arm 8.

In carrying out the present invention, one of the screws 12 for securing the bearing 10 intact is disposed through the opening 13 of the L-shaped bracket 14, the outstanding leg of which is provided with the notch 15 for receiving the arm 16 which projects from the collar 17 secured to the upper end of the shaft 18 by a set screw or the like 19.

The shaft 18 extends downwardly through the bearing protuberances 20—21 on the post 22 and has a fixed collar 23 at its intermediate portion between which and the bearing 20, a coiled compressible spring 24 is provided which tends to urge the shaft 18 downwardly to maintain the blade 25 carried by the lower end thereof tensionally against the elongated fixed blade 26.

As can be seen in Figures 1, 3 and 7, a bracket 27 is employed for supporting the post 22, the lower end of this bracket being provided with slots 28 through which securing means 29 are disposed for securing the bracket to the face of the machine. The upper end of this bracket 27 is provided with a laterally extending platform-like construction 30 upon which the post 22 is secured and also the elongated block 31 upon which the elongated secondary guide 32 is secured with the stationary scissors blade 26 superimposed thereon. Both the guide 32 and the blade 26 are provided with longitudinally extending slits 33 at one end through which the machine 40 screws 34 are disposed and into the block 31, thus permitting longitudinal adjustment of the guide 32 and blade 26 on the block 31.

The primary guide which is generally referred to by numeral 35 consists of the elongated arm 36 curved upwardly at its outer end portion as at 37. The same screws 29 are employed for securing the arm 36 in place.

The upper end of the arm 36 has the laterally disposed portion 38 on which the plate 39 is secured, this plate having converging side walls 40—40, the same converging toward the machine 5. Upon the wide portion of the plate 39 is the pressure plate 41, this pressure plate having openings therein with the studs 42 on the 55

wide portion of the plate 39 disposed therethrough to permit vertical movement of the pressure plate 41 on this end portion of the plate. The end portions 43-44 of the plate 41 and plate 39 are flared with respect to each other so that a strip of stitch tubing such as is referred to by numeral 45 can be readily fed through this guide 35.

Obviously the tubing 45 is first disposed through the guide 35 and over the secondary guide member 32. The end of the tube is brought between the blades 25-26 and the sewing machine started. As the eccentric arm 8 and rocking arm 7 begin to operate, an oscillatory motion is imparted to the arm 16 which pivots the scissors blade 25. As the feeding mechanism of the sewing machine pulls the tubing 45 the scissors thus operate to slit the tubing, and as the tubing is slit it is first spread apart by suitable spreading means 46 and subsequently contracted by the tapering structure 47 and as it passes this contracting structure the edge portions of the split tubing are brought against opposite sides of the edge portions of a garment 48 and subsequently sewed in this position by the machine 5.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. In combination, a sewing machine, a movable part of the sewing machine, a scissors structure secured to the base of the machine adjacent the standard of the overhanging arm to sever material as it advances to the sewing point and consisting of a stationary blade and a pivotal blade, a connection between the pivotal blade and the movable part of the sewing machine, and material guide means for guiding the material to the scissors, said guide means consisting of an elongated guide finger upon which the stationary blade is secured and beyond the free end of which the finger projects. 5

10 15 20 25 30

2. In combination, a sewing machine, a movable part of the sewing machine, a scissors structure secured to the base of the machine adjacent the standard of the overhanging arm to sever material as it advances to the sewing point and consisting of a stationary blade and a pivotal blade, a connection between the pivotal blade and the movable part of the machine, material guide means for guiding material to the scissors, said guide means consisting of an elongated guide finger upon which the stationary blade is disposed, securing means for said blade and guide finger, said securing means being common to both the stationary blade and guide finger, said stationary blade being provided with a longitudinal slot therein through which the said securing means is disposed. 30
